WASHER ATTACHMENT FOR ICE CRUSHERS

Harry A. Lehman, James A. Bateman, and
William W. Bateman, Mineral Wells, Tex.

Application October 1, 1948, Serial No. 52,292

3 Claims. (Cl. 241—62)

1

This invention relates to new and useful improvements in ice crushing machines and the primary object of the present invention is to provide a washer attachment for ice crushing machines.

Another important object of the present invention is to provide an attachment for ice crushing machines that will wash and clean blocks of ice prior to the placement of the same into the crushing chamber of an ice crushing machine thus permitting the delivered ice to be sanitary, a procedure not presently employed during the treatment of ice blocks.

Yet another object of the present invention is to provide a washer attachment for ice crushing machine including a cleaning chamber, a spray head for directing a fluid medium on ice blocks in the cleaning chamber and embodying novel and improved valve means controlling the spray head and which is actuated by a block of ice moved into the chamber.

A further object of the present invention is to provide an apparatus of the aforementioned character that is quickly and readily applied to or removed from an ice crushing machine in a convenient manner.

A still further aim of the present invention is to provide a washer attachment for ice crushing machines that is simple and practical in construction, strong and reliable in use, small and compact in structure, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts, throughout, and in which:

Figure 1 is a perspective view of an ice crushing machine and showing the present invention applied thereto;

Figure 2 is a top plan view of the present invention, and with parts thereof broken away and shown in section;

Figure 3 is a fragmentary longitudinal vertical sectional view of the present invention;

Figure 4 is a transverse vertical sectional view taken substantially on the plane of section line 4—4 of Figure 2; and

Figure 5 is a fragmentary perspective view and showing the spray nozzle used in conjunction with the present invention.

Referring now to the drawings in detail, where-

in for the purposes of illustration, there is disclosed a preferred embodiment of the present invention, the numeral 10 represents a substantially rectangular casing having one end 12 supported upon the ice crushing compartment 14 of an ice crushing machine that is designated generally by the numeral 16.

The forward or open end 18 of the casing 10 is supported relative to the bed of the machine 16 by a plurality of supporting legs or brace members 20.

Extending transversely between the sides of the casing 10, at the open forward end 18 thereof, is a removable bolt or pin 22 that pivotally receives a longitudinal sleeve 24 at one edge of a substantially rectangular shield or guard flap 26.

The inner and outer lower end walls 28 and 30 of the casing 10 are inclined and terminate in supporting flanges 32 to which there is rigidly secured a pair of spaced parallel, longitudinally extending guide rails 34.

Projecting laterally from opposite sides of the casing 10, at substantially the center thereof, is a pair of opposed substantially channel shaped projections 36 that communicate with the interior of the casing 10 and which are joined by an upper channel portion 38 disposed above the casing 10.

A transverse conduit 40 extends transversely between the sides of the casing 10, adjacent the channel portion 38 and above the upper wall of the casing 10, and supports arcuate extensions 42 at its ends that extend into the projections 36. The extensions 42 support spray nozzles 44 having arcuate discharge slots 46 that are disposed in the said projections for spraying a fluid medium into the casing 10.

Coupled to the conduit 40 by a joint 48 is one end of a delivery conduit of pipe 50 having a portion 52 that enters the casing 10 and which extends through the bottom wall 54 of the casing 10 and leads to a suitable source of liquid.

A T joint 56 coupled in the portion 52 supports an auxiliary conduit 58 the free end of which supports a spray head or nozzle 60 that will direct a fluid spray or stream upwardly into the casing 10.

A valve housing 62 is interposed in portion 52 of the conduit 50 and includes a suitable valve that is controlled by an upwardly and inwardly inclined operating lever 64 that is spring urged so that the same will be disposed above the guides 34.

In order to drain the washing medium from

the casing 10, there is provided a removable drain plug 66 that is suitably supported in an aperture or retaining ring in the bottom wall 54 of the casing 10.

In practical use of the present invention, a block or cake of ice is slid manually upon the guides 34 and as the same engages and bears against the operating lever 64, the valve in the housing 62 will be actuated to an open position whereby fluid under pressure will be directed through the nozzle 44 and 60 into the casing to effectively wash and clean the block of ice prior to the entrance of the same into the crushing compartment 14.

The shield 26 will prevent the washing medium from being deflected outwardly from the casing 10 to harmfully effect an operator feeding ice blocks into the casing 10.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In combination with an ice crushing machine, an apparatus for washing and cleaning ice prior to the disposal thereof into the crushing compartment of said machine, said apparatus being supported solely by and overlying the machine and comprising, a guide slidably supporting a block of ice and leading to said compartment, spray nozzles associated with the guide for supplying a fluid medium to ice on said guide, means for draining the fluid medium employed for washing and cleaning a block of ice on said guide, and a pressure actuated valve including a vertically inclined vertically swingable operating lever disposed in the path of movement of a block of ice slidably mounted on the guide for controlling the flow of fluid from the spray nozzles, said compartment being of sufficient length and width to prevent the hands of an operator from entering said compartment during the sliding of ice through the compartment, and hollow lateral projections carried by said casing communicating with the interior of said casing and receiving said spray nozzles.

55

2. An attachment for ice crushing machines having an open ended chute for receiving ice blocks, said attachment comprising a pair of side walls and an upper wall joining said side walls, each of said side walls having an elongated opening therein, a hollow channel member on each of said side walls, said channel members being in registry with said openings, a pair of horizontal guide rails mounted between said side walls, a drain trough mounted on said side walls and underlying said rails, a fluid supply line having branch lines entering said channel members, one of said branch lines entering and confined within said trough and being located between said rails, and a spray nozzle on each of said branch lines, at least one of said nozzles being confined within said trough and at least one of said nozzles being confined within each of said channel members to permit unrestricted sliding movement of a block of ice on said rails.

3. In an ice crushing machine having an ice crushing compartment and a supporting bed, an attachment for cleaning ice blocks prior to the entrance of ice blocks into the ice crushing compartment, said attachment being supported solely by said bed and overlying said compartment, said attachment comprising a pair of spaced parallel vertical side walls leading to said compartment, guide means mounted between said side walls and extending toward said compartment, a trough also mounted between said side walls and underlying said guide means, each of said side walls having a hollow lateral projection communicating with the space between the vertical walls, a spray nozzle confined completely within each of said projections, another spray nozzle confined completely within said trough, and conduit means attached to each of said nozzles.
